SUPPORTING FRAME FOR GLIDERS OR
THE LIKE

Louis Vavrik, Toledo, Ohio, assignor to The Hetrick Manufacturing Company, Toledo, Ohio, a corporation of Ohio

Application August 28, 1936, Serial No. 98,368

2 Claims. (Cl. 5—129)

This invention relates to articles of furniture but more particularly to supporting frames for gliders or the like and an object is to produce a new and improved frame of this character which is simple and inexpensive to manufacture, can be conveniently assembled for use without the necessity of nuts, bolts or tools and has the novel features of construction and arrangement hereinafter described.

10 The invention is shown by way of illustration in the accompanying drawing in which;

Figure 1 is a perspective view of the glider supporting frame;

Figure 2 is an enlarged bottom plan view of a portion of the connecting rail and end frame, showing the brace arms in position of use; and

Figure 3 is a vertical sectional view on the line 3—3 of Figure 1.

The illustrated embodiment of the invention 20 comprises a glider supporting frame, having upright end frames 10 and 11 which are connected together by a connecting rail 12. It will be understood that the glider is supported by the end frames 10 and 11 upon hangers 13 which depend from the upper portion of the end frames.

Each end frame is made up of a single strip of bar metal to provide a horizontally disposed upper bar 14 and a horizontally disposed lower bar 15 and curved sides 16 and 17. Extending upwardly 30 from the inner side of the lower bar 15 is a flange 18 and secured centrally thereto, as by spot welding, is a supporting member 19, the upper end of which inclines inwardly and is notched at 20. Secured to the under side of the lower bar 15, adjacent opposite ends thereof, are supporting knobs 21 which dispose the end frames slightly above the supporting surface. It will be understood that the end frames 10 and 11 are similarly constructed and description of one will suffice.

40 The connecting rail 12 is preferably in the form of a metal tube or rod and is substantially U-shaped in formation. The legs 22 of the rail are of a length substantially equal to the distance between the top bar 14 and the support 19 so that opposite ends of the rail 12 in the region of the bends fit into and are supported by the supports 19, the notch 20 being shaped to receive the same. The extreme upper ends of the legs 22 fit respectively into socketed members 23 which are 45 suitably secured to the underside of the top rail 14. As indicated in Figure 3, the end of each leg 22 extends well into the socketed member 23 and which, in cooperation with the notched support, militates against lateral displacement between the 50 end frames and the connecting rail 12.

For bracing the connecting rail and adjacent end frames a pair of arms 24 and 25 have a common pivot 26 at their inner ends and are attached

5 to the under side of the rail 12. Formed on the free ends of the arms 24 and 25 are notches 27 which are adapted to slip over headed pins 28 on the under side of the lower bar 15. As shown in Figure 2 the arms 24 and 25 extend at an angle to the rail 12, one being disposed on each side thereof. Pivoted latches 29 connected to the under side of the lower bar 15 are arranged adjacent each of the pins 28 so that when the notched portions 27 are moved into engagement with their respective pins, the pivoted latch 29 can be swung against the arm to retain the parts in assembled position. When it is desired to disassemble the parts, it will be apparent that the latches 29 can be readily swung out of engagement with the 15 brace arms to permit the latter to be disengaged.

10 From the above description it will be apparent that I have provided an exceedingly simple frame construction which can be inexpensively manufactured and which can be set up in a short time 20 by any unskilled person without the use of bolts, nuts or tools. When assembled the frame is sturdy and reliable and provides a satisfactory support for a glider or other similar article of furniture.

25 It is to be understood that changes may be made in details of construction and arrangement without departing from the spirit of the invention, especially as defined in the appended claims.

What I claim as new and desire to secure by 30 Letters Patent is:

1. A glider supporting frame comprising a pair of laterally spaced upright end frames, each end frame having a transverse bar at the upper end thereof, a socket member in the under portion of said bar, a saddle on the lower portion of each end frame, a substantially U-shaped tube having the upper ends fitting into and embraced by said socket members, another portion of said tube resting in the saddle of each frame, and a pair 35 of brace arms pivoted respectively to spaced portions of the tube adjacent each end frame, and detachable fasteners for holding the opposite ends of said braces in engagement with said end frames.

40 2. A glider supporting frame comprising a pair of laterally spaced upright end frames, each end frame having a transverse bar at the upper end thereof, a socket member in the under portion of said bar, a saddle on the lower portion of each 50 end frame, a substantially U-shaped tube having the upper ends fitting into and embraced by said socket members, another portion of said tube resting in the saddle of each frame, braces for connecting the tube to each end frame respectively, and detachable fasteners for retaining said braces in operative position.

LOUIS VAVRIK.
